WATER SOFTENING APPARATUS

Andrew J. Dotterweich, Pittsburgh, Pa., assignor,
by mesne assignments, to General Water
Treatment Corporation, New York, N. Y., a
corporation of Delaware

Application July 8, 1924, Serial No. 724,804

47 Claims. (Cl. 210—24)

The invention described herein relates to certain improvements in the practice of softening water as described and claimed in an application Serial No. 647,607 filed by me March 7, 1934.

5 The invention is hereinafter more fully described and claimed.

In the accompanying drawings forming a part of this specification, Fig. 1 illustrates diagrammatically a valve mechanism, its operating motor, 10 solenoids, and controlling circuits, for regulating the flow of water to and from a tank containing a water softening material in the proper sequence for softening the water, backwashing the material, regenerating the material, and removing the 15 brine from the material and resuming the softening operation; Figs. 2 and 3 are sectional views of the valve mechanism showing different positions of the movable member; Fig. 4 is a top plan view of the apparatus; Fig. 5 is a sectional elevation of the brine tank, its outlet valve and operating mechanism; in Fig. 6 are shown views illustrating the sequence of operation of make and break devices controlling the certain circuits.

In the practice of the invention the shell 1 of 25 the controlling valve mechanism is preferably secured in any suitable manner to the tank A, containing the material employed for softening water, e. g., zeolite, and has ports 2 and 3 in its upper and lower ends in constant communication 30 through pipes 4 and 5 with the tank at points above and below the body of softening material in the tank. The movable member 6 of the valve mechanism is provided with a chamber 7 in constant communication with the upper portion of 35 the tank through port 2 and pipe 4, and with a chamber 8 in constant communication with the lower portion of the tank through port 3 and pipe 5. A pipe 9 extending from the water supply is connected by branches 10 and 11 to inlet 40 ports 12 and 13 in the valve casing 6, said ports being so located in such relation to the chambers 7 and 8 in the member that inlet ports 14 and 15 through the walls of the respective chambers may be brought into register with the respective ports 45 12 and 13 by the movement of the member 6 as hereinafter described. A pipe 16 extends from an outlet port 17 in the valve shell or casing to a point of use, said port being so located that an outlet port 18 in the wall of the lower chamber 50 of the member 6 may be brought into register therewith, as hereinafter described.

A pipe 19 extends from a timing tank B and is connected by branches 20 and 21 to ports 22 and 23 in the valve casing, said ports being so located 55 that by the proper movements of the member 6

ports 24 and 25 in the walls of the chambers 7 and 8 may be brought into register with the ports 22 and 23. This timing tank, by means of which the duration of the backwashing period is determined, as hereinafter described, is connected 60 by branches 26 and 27 to a pipe 28 extending to a drain or sewer. As shown, the branches are connected at different levels to the tank and the lower branch 27 is provided with a valve 29 whereby the flow through the branch 27 relative to the 65 inflow through pipe 19, may be regulated.

The brine tank C has an outlet port 30 connected by a pipe 31 to the pipe 9 extending as stated from the water supply. The flow through the port 30 is controlled by a valve 32. When the latter is opened as hereinafter described, the brine will be drawn from the tank by the flow of water in the pipe 9, and mingling with the water, pass into the tank A.

While any suitable means may be employed for 75 oscillating the valve 6 and moving the brine controlling valve 32 to open position, it is preferred to employ electrically operated means, as for example, solenoids for that purpose. As will be seen by reference to Figs. 1, 2, 3, and 4, the movable member 6 of the valve mechanism is provided 80 with a stem 33 on which is secured oppositely disposed arms 34 having their outer ends connected to the armatures 35 of the respective coils 36 and 37. When the circuits through both coils 85 are broken the valve is returned to normal position by means of springs 38 and held in such position by conjoint action of said springs. It should be understood that when the valve member 6 is in normal position, water will flow from 90 the supply through the material in tank A to the point of use.

Before proceeding with the description of the circuits employed attention is called to the fact that for the sake of clearness of illustration, make 95 and break devices, which are operated by and in accordance with the movements of the valve are shown separated therefrom in the diagram, illustrating the circuits (Fig. 1). The circuit for the coil 36 consists, starting from the generator 100, of the conductors 39, 40 and 41, terminals 42, contact plate 43, conductor 44, coil 36, conductors 45, 46, terminal 47, contact plate 48, conductors 49 and 50 to generator. The contact plate 43 for connecting the terminals 42 is carried by 105 a disc 51 on the valve stem 33, and the contact plate 48 is carried by an oscillating head 52 operative by and in accordance with the changes of level of water in the timing tank B. The head 52 is loosely mounted on a shaft 53 as is also one 110

end of an arm 54 which extends down into the tank B and carries a float 55. The head 52 and arm 54 are connected at points distant from their center of movement by a spring 56 so that when 5 the float moves up such a distance that the spring passes above the shaft 53, the head 52 will be raised thereby shifting the plate 48 out of contact with the terminals 47.

As shown in Fig. 1 the circuit above described is 10 normally open, but in order to start the operation involved in regenerating, a by-circuit 57 including a suitable hand operated switch 58 is employed for closing and holding closed the described circuit until by the movement of the valve 6 the 15 plate 43 is shifted into contact with the terminals 42. On the closure of the switch 58, the solenoid 36 will be excited and its armature drawn in thereby through the arm 34 shifting the valve 6 to the position shown in Fig. 2, moving the port 20 14a out of alignment with the port 12, and moving the port 15 into register with the port 13, and the port 24 into register with the port 22. When the valve is in this position, water from the supply will flow into the chamber 8 of the valve, thence 25 through port 3 to the lower end of the tank A, up through the tank pipe 4 and port 2 into the chamber 7 of the valve carrying with it any foreign matter deposited in the charge of regenerating material in the tank. From the chamber 7 the 30 water will flow through the ports 24 and 22 and pipe 19 to the timing tank from which the water will flow first through branch 27 and pipe 28 to a drain. The valve 29 in branch 27 is so adjusted that the rate of escape of water will be less than 35 the inflow from the treating tank A, until the water rises in the tank to the level of the branch 26. As the water rises in the tank the float 55 will be lifted until the spring 56 passes above the shaft 53 and shifts the head 52 in a direction to 40 move the plate 48 away from the terminals 47, thereby breaking the circuit through the solenoid 36 and permitting the arm 34 and valve 6 to be shifted by the spring 38 to normal position, stopping the flow of water to the timing tank. It will 45 be readily understood that by the adjustment of the valve 29 the duration of the backwashing can be varied as desired. The return of the valve to normal following the movement of the head 52 as above described, will move the disc 51 to the position shown in Fig. 1 thereby moving the plate 43 out of contact with the terminals 42.

The backwashing is followed by the admission of brine to the tank A for regenerating the material contained therein. The admission of the 55 brine is effected by a movement of the valve 6 in a direction the reverse of that whereby the backwashing is effected, and hence provision is made for energizing the solenoid 37 immediately subsequent to the breaking of the circuit through 60 the solenoid 36. The circuit of the solenoid consists, starting from the generator 100, of the conductors 50, 59, terminals 60, contact plate 61, conductor 62, solenoid 63, conductor 64, solenoid 37, conductor 65, terminals 66, contact plate 67, conductor 68 and 39 to generator. The contact plate 61 is secured to head 69 provided with a tail 70 and so pivotally mounted that the end of the tail will be engaged to shift the head by a cam projection 71 on the disc 51 on the stem 33 of the 70 valve 6. Springs 72 are employed for returning the head to mid position after being shifted by the cam. The sequence of the movements of the contact plates 43 and 61 in making and breaking the described circuits of the solenoids 36 and 75 51 is illustrated by the several views included in

Fig. 6. View a shows the normal relative positions of the several parts, i. e., during the softening period. When the circuit of solenoid 36 is closed by the operation of the switch 58, as hereinbefore described, the disc 51 is rotated in the direction of the arrow causing the plate 43 to contact with the terminals 42. This movement of the disc moves the head 69 to the right sufficiently far to permit the cam 71 to pass under the end of the tail and the head be returned to mid position by the springs 72. When the circuit through solenoid 36 is opened by the described movement of the head 52, the valve 6 and the disc will be shifted by a spring 38 to normal position. This movement of the disc in the direction indicated by the arrows in views d and e, Fig. 6, will shift the head 69 to the left, thereby bringing the plate 61 on the head into contact with the terminals 60. As shown in Fig. 1 the plate 67 forming part of the described circuit of solenoid 37 is so secured to the head 52 that when the latter is raised as the water in the timing tank reaches a predetermined level to break the circuit through solenoid 36, the plate 67 will be moved into contact with the terminals 66 of the circuit of the 100 solenoid 36. Thus it will be seen that the movements of the parts whereby one circuit is broken, will effect the closing of the other circuit.

The movement of the valve 6 due to the energizing of the solenoid 37 will bring a port 14a 105 in the wall of the chamber 7 into alignment with the port 12 connected as described to the branch 10 in the water supply pipe 9 and a port 25 in the wall of chamber 8 will register with the ports 23 in the valve shell connected to the 110 tank B, as shown in Fig. 3. Simultaneous with the closing of the circuit through solenoid 37, the valve 32 controlling the flow of brine from the tank C into the supply pipe 9, is opened. The valve 32 (Fig. 5) is connected to a lever 73 115 forming the armature of the electro-magnet or solenoid 63. The valve 6 being in the position above described and shown in Fig. 3, the flow of the brine will be down through tank A into tank B and thence to a drain. Suitable means 120 for controlling the duration of flow of brine through the tank are employed, such for example as that shown in Fig. 1. Suitably spaced terminals 74 are inserted into the pipe 28 leading to the drain. These terminals form portions 125 of a circuit including an electro-magnet 75. This branch circuit will be closed by the presence of salt in the water flowing through the drain. From the legs of the circuit through the solenoid extend conductors 76 and 77, having terminals in operative relation to the armature 78 of the electro-magnet 75 which is drawn into contact with the terminals on the closure of the branch circuit by the salt water.

The conductors 76 and 77 and armatures 78 130 form a short circuit around the electro-magnet 63, so that as soon as salt water electrically connects the terminals 74 the valve 32 will be closed by a spring 73a connected to the lever 73. This short circuiting of a portion of the circuit does not affect the solenoid 37, and hence water free from brine will continue to flow through tank A and out through the drain for a sufficient time to wash out all traces of salt 140 in the material in the tank.

The cam projection 71 on the disc 51 is made of such peripheral length that it will pass from under the tail 70 permitting the head 69 to be returned to normal position by the springs 72, thereby moving the plate 61 on the head 69 out 150

of contact with the terminals 60. A make and break device is connected in multiple arc to the circuit at a point intermediate the electro-magnet 63 and the terminals 60. This make and break device is controlled by means employed for operating the brine valve 32. A desirable construction consists, as shown in Fig. 1 of a contact plate 79 on the lever 73 and terminals 80 so located that when the lever is shifted to open the brine valve 32, the plate will close the main circuit.

It will be understood that the contact plate 61 is made of such a length that circuit completed thereby will remain closed sufficiently long to permit of the lever 73 being shifted and the plate 79 moved into contact with the terminals 60 of the supplemental circuit. When the electro-magnet 63 is short circuited on the completion of the circuit through the electro-magnet as hereinbefore described, the lever will be shifted by its spring and the plate 79 moved from contact with the terminals 80 of the supplemental circuit and thereafter the circuit through the solenoid is controlled by the magnet 75 and will remain closed as long as the water flowing to the drain contains sufficient salts to render it conductive. As soon as the water free from salt flows through the drain, the magnet 75 will become de-energized and the armature 78 will be shifted by its spring away from the terminals of conductors 76 and 77 thereby opening the circuit through the solenoid 37 thereby permitting the valve 6 to be shifted by its spring, 38, to normal position in which position water will flow through the tank A and softened water will flow to the point of use.

As the switch 58 by the closure of which the regenerating operations are initiated, may be located at a distance from the apparatus, a signal is provided adapted to indicate the movement of the valve 6 to position for backwashing. This signal 80 is preferably electrically operated and is connected across the circuit of the solenoid 36 as shown in Fig. 1. A signal 81 is also provided to indicate that the valve 6 is in position for directing brine and wash water to the tank A, said signal which may be audible or visual has its circuit connected across the circuit of the solenoid 37.

The operation of the apparatus in the regeneration of the softening material and the softening period is briefly as follows:—

Assuming that the softener is exhausted and ready to be regenerated, the operation of regeneration is initiated by pressing the push button station 58. This energizes the solenoid 36 which actuates the valve 6 to move it from the mid position to cause water to enter chamber 8 from which it passes down through the lower inlet 5 thence upwardly through the zeolite material to backwash it and out at the upper outlet 4 to chamber 7 from which it is conducted through the piping 19 to the timing tank and thence through the outlets 26 and 27 to the drain.

With the shifting of the valve 6, the contact 43 closes the terminals 42 to take the place of initial contact made by push button 58. The lower outlet 27 of the timing tank is controlled by valve 29 so that the water flowing through the drain will be less than the volume entering through the conductor 19 the excess flowing to the tank will gradually fill the same, the filling of the tank requiring a predetermined length of time, and when full, the water will escape to the drain

through the upper outlet 26 which is sufficiently large to permit the excess water to escape.

The filling of tank B will cause the float 55 to lift, which in turn shifts the member 52 to bring the movable contacts 67 into contact with the member 66 at the same time opening contacts 47 which control the solenoid 36. In making the contact at 66, solenoid 37 which controls the salting and flushing operations, becomes energized and actuates the valve 6 to move it to the opposite side, thus permitting the water and salt solutions to pass through the pipe 9 to the upper chamber 7, thence through the upper inlet 4 and down through the zeolite bed from which it passes from the lower outlet 5 into chamber 8, thence through pipe 19 to tank B and subsequently through the drain.

Simultaneously with the energizing of the solenoid 37, the movable contact 61 is brought into engagement with the stationary contact 60 for a sufficient length of time to cause the circuit controlling the solenoid 63 of the salt tank to become energized whereby a supplemental circuit is established by the contacts made through the actuation of the solenoid 63. When this supplemental circuit is established, contacts a 60 are broken by the member 51 which operates the movable contact member 70 and the latter in the mid position of valve 6, closes contact 60 and in the off position, that is, when either of the solenoids 36 or 37 is energized, opening the contacts at 60.

With the solenoid 63 energized, salt is drawn from the brine tank through the softener and eventually to the drain. The terminals 74 in the drain line having in circuit the magnets 75 is adjusted to energize the latter when a brine solution is passing to the drain, the brine solution being the shunting element in establishing the circuit across the terminals 74. When such a brine solution passes through the drain, the solenoid 63 becomes short circuited, but the solenoid 37 controlling the flow of brine to the drain will remain energized.

With solenoid 63 short circuited, the spring 73a closes the salt valve at the same time opening the contacts controlling solenoid 63. Eventually when the salt is washed out of the softener and the drain, the circuit across the terminal 74 can no longer be maintained, thus permitting the contact 78 to open the circuit controlling the solenoid 37, whereby the valve 6 moves into mid-position to which it is normally biased by springs, this position being the position in which the softening apparatus is again rendered operative and in which position the water will pass through the line 9 into chamber 7 thence to the top inlet down through the zeolite bed and out at the lower inlet 5 into chamber 8 and to the point of use through the pipe 16.

I claim herein as my invention:

1. In an apparatus for softening water, the combination of a tank containing material for softening water, a timing tank, a reversible valve mechanism, means for shifting the valve to a position where water may flow from a supply to one end of the softening tank and from the opposite end of the latter to the timing tank, and means operative by and in accordance with changes of level of water in the timing tank for shifting the valve to permit water to flow to the upper end of the softening tank without checking the flow of water from the tank.

2. In a water softening apparatus the combi-

- nation of a tank containing material for softening water, a timing tank, a valve mechanism for controlling the flow of water from a supply to the softening tank and from the latter to the timing tank, means for regulating the discharge of water from the timing tank, and a float in said tank, and means operative by the float for shifting said valve mechanism. 80
3. In a water softening apparatus the combination of a tank containing material for softening water, a timing tank, a valve mechanism for controlling the flow of water from a supply to the softening tank and from the latter to the timing tank, said timing tank having vertically spaced outlets having a united discharge capacity of not less than the rate of flow to the tank, a valve in the lower outlet, a float arranged in the tank and means operative by said float for shifting the valve controlling the flow 90 from the softening tank to the timing tank. 95
4. In a water softening apparatus comprising a tank containing material for softening water, a source of water connected to the tank, a draw-off pipe leading to a point of use, a draw-off pipe leading to a waste point, a valve mechanism controlling said draw-off pipes, a source of brine for regenerating the softening material, valves for controlling the flow of brine through the softening material and out the draw-off pipe to the waste point, and an electrically operated signal controlled by a circuit closed by brine in the draw-off to waste pipe, whereby the signal indicates completion of passage of brine from the softening tank by breaking of the said circuit. 100
5. In a water softening apparatus having a brine tank and a softening tank and a circulating system of piping therefor, valve mechanism therefor having a valve controlling circulation from the brine tank to the softening tank and a valve controlling circulation from the softening tank to a waste pipe, magnets for actuating said valves, and a switch controlled circuit for said magnets including a short circuit connection with an electrode in the circulating piping for short circuiting the circuit of the magnet for the brine valve. 110
6. In a water softening apparatus having a brine tank and a softening tank and a circulating system of piping therefor, valve mechanism therefor having a valve adapted to control circulation from the brine tank to the softening tank and a valve adapted to control circulation from the softening tank to a waste pipe, magnets for actuating said valves and a switch controlled circuit for said magnets including a short circuiting connection with an electrode in the waste pipe whereby the magnet for the first valve is de-energized and the magnet for the second valve is retained in the circuit. 120
7. In a water softening apparatus having a brine tank and a softening tank and a circulating system of piping therefor, valve mechanism therefor having a valve adapted to control circulation from the brine tank to the softening tank and a valve adapted to control circulation from the softening tank to a waste pipe, magnets for actuating said valves, an energizing circuit therefor, and an electrode in the circulating system connected with said circuit for short circuiting the magnet of the valve controlling circulation from the brine tank to the softening tank whereby the magnet for the first valve is de-energized and the magnet for the second valve is retained in the circuit. 130
8. In a water softening apparatus having a softening tank and a brine tank, and a circulating system of piping therefor, valve mechanism for controlling circulation from the brine tank to the softening tank, a valve controlling circulation from the softening tank, and electro-magnetic means responsive to the relative conductivity of the fluid flowing from the softening tank for actuating said control valves. 140
9. In a water softening apparatus having a softening tank and a brine tank and a circulating system of piping therefor, means for circulating brine through the softening tank to regenerate the softening material and electrically operated means responsive to the relative conductivity of the fluid flowing from the softening tank for terminating the flow of brine to the softening tank. 150
10. In a water softening apparatus having a softening tank and a brine tank, and a circulating system of piping therefor, a valve controlling circulation from the brine tank to the softening tank, a valve controlling circulation from the softening tank to a waste pipe, magnets for actuating said valves, and a switch controlled circuit for said magnets including a short circuit connection with an electrode in the waste pipe for short circuiting the circuit of the magnet for the brine valve. 155
11. In a water softening apparatus having a softening tank and a brine tank, and a circulating system of piping therefor, a valve controlling circulation from the brine tank to the softening tank, a valve controlling circulation from the softening tank to a waste pipe, magnets for actuating said valves, and a switch controlled circuit for said magnets including a short circuit connection with an electrode in the waste pipe, whereby the magnet for the first valve is de-energized and the magnet for the second valve is retained in the circuit. 160
12. In a water softening apparatus having a softening tank and a brine tank, and a circulating system of piping therefor, means for circulating brine through the softening tank to regenerate the softening material and electrically operated means responsive to the relative conductivity of the fluid flowing from the system for initiating the flow of water to flush out the brine solution. 170
13. In a water softening apparatus having a softening tank, a brine tank, and piping therefor, a drain leading from said softening tank, valve mechanism controlling the circulation from the brine tank to the softening tank, and electrically operated means responsive to the relative electrical conductivity of the fluid flowing to the drain for operating said valve mechanism to terminate the flow of brine to the softening tank. 180
14. In a water softening apparatus having a softening tank, a brine tank and piping therefor, a drain leading from said softening tank, valve mechanism controlling the circulation from the brine tank to the softening tank, and electrically operated means responsive to the character of the fluid flowing to the drain for operating said valve mechanism to terminate the flow of brine to the softening tank. 190
15. In a water softening apparatus having a softening tank, a brine tank and piping therefor, a drain leading from said softening tank, valve mechanism controlling the circulation from the brine tank to the softening tank, and electrically operated means responsive to the character of the fluid flowing to the drain for operating 195

ing said valve mechanism to determine the volume of brine flowing to the softening tank.

16. In a water softening apparatus having a softening tank, a brine tank, and piping therefor, a drain leading from said softening tank, electrically operated means controlling the flow of fluid from the brine tank to the softening tank and electrodes disposed in the drain leading from the softening tank and adapted to control said electrically operated means for determining the volume of brine solution passing to said softening tank.

17. In a water softening apparatus having a softening tank, a brine tank and piping therefor, a drain leading from said softening tank, electrically operated means controlling the flow of fluid from the brine tank to the softening tank and electrodes disposed in the drain leading from the softening tank and adapted to control said electrically operated means to terminate the flow of fluid from the brine tank.

18. In a water softening apparatus having a softening tank, a brine tank and piping therefor, a drain leading from said softening tank, electrically operated means controlling the flow of flush out water to the softening tank, electrodes disposed in the drain leading from the softening tank and adapted to control the said electrically operated means to initiate the flow of flush out water to the softening tank.

19. In a water softening apparatus having a softening tank, a brine tank and piping therefor, a drain leading from the said softening tank, electrically operated means controlling the flow of fluid from the brine tank to the softening tank and for controlling the flow of flush out water to the softening tank and electrodes disposed in the drain leading from the softening tank and adapted to control said electrically operated means to determine the volume of brine passing to said softening tank and the volume of flush out water passing through the softening tank.

20. In a water softening apparatus a softening tank, a brine tank, a system of piping therefor, valves controlling the flow of brine from the brine tank to the softening tank and flush out water to the softening tank, and means for controlling the said valves, said means being responsive to the character of water flowing to the drain to terminate the flow of brine to the softening tank to initiate the flow of flush out water to the softening tank, to terminate the flow of flush out water to the softening tank, and to restore the softener to normal operation of softening water passing from a source of water supply to a point of use.

21. In a water softening apparatus, a tank containing softening material, a salt tank and system of piping therefor, valve mechanism controlling the flow of fluid through said piping and electrical means responsive to the change in character of the water passing from the softener tank for actuating said valve mechanism to determine the duration of the period of salting and to determine the duration of the period of washing.

22. In a water softening apparatus, a tank containing softening material, a salt tank and system of piping therefor, valve mechanism controlling the flow of fluid through said piping and electrical means responsive to the change in character of the water passing from the softener tank for actuating said valve mechanism to determine the duration of the period of salting, to determine the duration of the period of washing

and subsequently cause the apparatus to be restored to the softening operation.

23. In a water softening apparatus, a tank containing softening material, a tank containing material for regenerating the softening material, a system of piping therefor, valve mechanism controlling the flow of fluid through said piping, means for actuating said valve mechanism and means controlled by the fluid flowing from said softener tank causing said valve mechanism to operate and terminate the flow of regenerating material to the softening material.

24. In a water softening apparatus, a tank containing softening material, a tank containing material for regenerating the softening material, a system of piping therefor, valve mechanism controlling the flow of fluid through said piping, and means controlled by the fluid flowing from said softener tank for actuating said valve mechanism to terminate the flow of regenerating material to the softening material and for actuating said valve mechanism to terminate washing of the softening material.

25. In a water softening apparatus, a tank containing softening material, a tank containing material for regenerating the softening material, a system of piping therefor, valve mechanism controlling the flow of fluid through said piping and means controlled by the fluid flowing from said softener tank for actuating said valve mechanism to terminate the flow of regenerating material to the softener material, to initiate the period of washing and subsequently for actuating said mechanism to terminate the washing of the softening material.

26. In a water softening apparatus, a tank containing softening material, a tank containing material for regenerating the softening material, a system of piping therefor, valve mechanism controlling the flow of fluid through said piping, means controlled by the fluid flowing from said softener tank to actuate said valve mechanism to terminate the flow of regenerating material to the softening material to actuate said valve mechanism to terminate washing of the softening material and subsequently to cause the apparatus to be restored to the softening operation.

27. In a water softening apparatus, a tank containing softening material, a tank containing material for regenerating the softening material, a system of piping therefor, valve mechanism controlling the flow of fluid through said piping, means controlled by the fluid flowing from said softener tank for actuating said valve mechanism to terminate the flow of regenerating material to the softening material, to initiate the period of washing, to terminate the washing of the softening material and subsequently to cause the apparatus to be restored to the softening operation.

28. In a water softening apparatus, a tank containing softening material, a tank containing material for regenerating the softening material, a system of piping therefor, valve mechanism controlling the flow of fluid through said piping, means controlled by the fluid flowing from said softener tank for actuating said valve mechanism to determine the volume of regenerating material passing to the softener tank.

29. In a water softening apparatus, a tank containing softening material, a tank containing material for regenerating the softening material, a system of piping therefor, valve mechanism controlling the flow of fluid through said

- piping, and means controlled by the fluid flowing from said softener tank for actuating said valve mechanism to determine the volume of regenerating material passing to the softener tank 5 and to control the volume of wash water passing from said softener tank.
30. In a water softening apparatus, a tank containing softening material, a tank containing material for regenerating the softening material, a system of piping therefor, valve mechanism controlling the flow of fluid through said piping, and means controlled by the fluid flowing from said softener tank for actuating said valve mechanism, to control the volume of regenerating material passing to the softener tank, to terminate the flow of regenerating material, to the softener tank, to initiate the flow of wash water through said softening tank, to control the volume of wash water passing through said softening tank, to terminate the flow of wash water through said softening tank and subsequently to cause the apparatus to be restored to the softening operation.
31. In a water softening apparatus, a tank containing softening material, a tank containing material for regenerating the softening material, a system of piping therefor, valve mechanism controlling the flow of fluid through said piping and means controlled by the fluid flowing from said softener tank for actuating said valve mechanism to initiate the flow of regenerating material to the softening material, to terminate the flow of regenerating material to the softening tank, to initiate the flow of wash water through said softener tank to terminate the flow of wash water and subsequently to cause the apparatus to be restored to the softening operation.
32. In a water softening apparatus, a tank containing softening material, a brine tank containing material for regenerating the softening material, a system of piping therefor, valve mechanism controlling the flow of fluid through said piping, and means controlled by the fluid flowing from said softener tank for actuating said valve mechanism to initiate the period of salting, to control the volume of brine passing to the softener tank, to terminate the flow of brine to the softener tank, to initiate the flow of wash water through said softener tank, to control the volume of wash water passing through said softener tank, to terminate the flow of wash water through said softener tank and subsequently to cause the apparatus to be restored to the softening operation.
33. In a water softening apparatus, a container for softening material, a tank containing material for regenerating the softening material, a system of piping therefor, valve mechanism for controlling the flow of fluid through said piping, means responsive to the character of the fluid flowing from said softening material for actuating said valve mechanism to terminate the flow of regenerating material to the softening material and subsequently to initiate the period of washing.
34. In a water softening apparatus, a container for softening material, a source of regenerating material, a system of piping therefor, valve mechanism for controlling the flow of fluid through said piping, means responsive to the character of the fluid flowing from said softening material for actuating said valve mechanism to control the volume of regenerating material passing to the softener, to terminate the flow of
- regenerating material to the softening material, to initiate the period of washing, to control the volume of wash water passing through the softener tank, to terminate the flow of wash water through the softener and subsequently to cause the apparatus to be restored to the softening position. 80
35. In an automatic water softening apparatus, a container for a softening material, a tank containing material for regenerating the softening material, a system of piping therefor, valve mechanism controlling the flow of fluid through said piping, electrical means for actuating said valve mechanism and means operative by the fluid flowing from said softener tank for breaking a circuit connecting said electrical means whereby delivery of the regenerating material to the softening means is terminated. 85
36. In an automatic water softening apparatus, a container for a softening material, a tank containing material for regenerating the softening material, a system of piping therefor, valve mechanism controlling the flow of fluid from the tank containing the regenerating material to the container for the softening material, from the source 90 of supply to the softening material to a point of use and to a drain, means to initiate a cycle of operations in which the apparatus passes through regeneration and returns to normal, and means controlled by flow of a predetermined volume of water from the softening tank for timing the flow of regenerating material to the softener tank after the cycle has been initiated. 95
37. In a water softening apparatus, a tank containing softening material, a brine tank and a system of piping therefor, valve mechanism controlling the flow of fluid through said piping, said mechanism being responsive to the passage of a predetermined quantity of water through the softening material to terminate the flow of such water and to initiate the period of salting, and means controlled by the fluid flowing from said softener tank for actuating said valve mechanism to determine the volume of brine passing to the softener tank, to terminate the flow of brine to the softener tank, to initiate the flow of wash water through said softening tank, to determine the volume of wash water passing through said softening tank, to terminate the flow of wash water through said softening tank and subsequently to cause the apparatus to be restored to the softening position. 100
38. In a water softening apparatus, a tank containing softening material, a salt tank and a system of piping therefor, valve mechanism controlling the flow of fluid through said piping, said mechanism being responsive to the passage of a predetermined quantity of water through the softening material to terminate the flow of such water and to initiate the period of salting, and means responsive to the character of the fluid flowing from said softening material for actuating said valve mechanism to terminate a flow of salt solution to the softening material, to initiate the period of washing, to terminate the flow of wash water through the softener and subsequently to cause the apparatus to be restored to the softening position. 105
39. In a water softening apparatus, a tank containing softening material, a brine tank and a system of piping therefor, valve mechanism controlling the flow of fluid through said piping, said mechanism being responsive to the passage of a predetermined quantity of water through said softening material to terminate the flow of such 110

- water and to initiate the period of salting, and means responsive to the character of the fluid flowing from said softening material for actuating said valve mechanism to determine the volume of brine passing to the softening tank, to terminate the flow of brine to the softener tank, to initiate the flow of wash water through said softening tank, to determine the volume of wash water passing through said softening tank, to terminate the flow of wash water through said softening tank and subsequently to cause the apparatus to be restored to the softening position. 5
40. In a water softener having a circulation system for normally flowing water to be softened through the softener to a service pipe and for flowing regenerating solution and water successively through the softener to a drain for regenerating and flushing operations, valves controlling said system, an electromagnet having a circuit controlled by the drain effluent, and means controlled by said magnet to close a valve controlling the admission of regenerating solution to the softener and to retain open a valve controlling flow from the softener to the drain. 15
25. 41. In a water softener having a circulation system for normally flowing water to be softened through the softener to a service pipe and for flowing regenerating solution and water successively through the softener to a drain for regenerating and flushing operations, valves controlling said system, an electromagnet having a circuit controlled by the drain effluent, and means controlled by said magnet to hold the valves in regenerating position during the regenerating period and to set the valves for flushing at the termination of said period. 30
35. 42. In a water softener having a circulation system for normally flowing water to be softened through the softener to a service pipe and for flowing regenerating solution and water successively through the softener to a drain for regenerating and flushing operations, valves controlling said system, an electromagnet having a circuit controlled by the drain effluent, and means controlled by said magnet to change the valves from position for regeneration to position for flushing and retain them in the latter position during the flushing period and then to set the valves for softening operation. 40
45. 43. In a water softener having a circulation system for normally flowing water to be softened through the softener to a service pipe and for flowing regenerating solution and water successively through the softener to a drain for regenerating and flushing operations, valves controlling said system, an electromagnet controlled by the drain effluent, the control of said magnet determining the periods for setting the valves to terminate regeneration and flushing respectively, and means controlled by said magnet for setting the valves for flushing at the termination of 50
- the regenerating period and for setting the valves for softening operation at the termination of the flushing period. 55
44. In a water softener having connections for supplying water and brine thereto and service and drain delivery connections, a normally closed brine valve, a normally open service valve and normally closed drain valve, valve controlling means operable to open the brine valve and drain valve and close the service valve, and an electromagnet controlled by the drain effluent and controlling the said means to close the brine valve and retain the drain and service valves respectively open and closed for a flushing operation. 80
45. In a water softener having connections for supplying water and brine thereto and service and drain delivery connections, a normally closed brine valve, a normally open service valve and normally closed drain valve, valve controlling means operable to open the brine valve and drain valve and close the service valve, and an electromagnet controlled by the drain effluent and controlling the said means to close the brine valve and retain the drain and service valves respectively open and closed for a flushing operation. 85
- 90
46. In a water softener having means for flowing brine and water successively through the softener to a drain for regeneration and flushing, an electromagnet having a circuit controlled by the effluent discharged to the drain to energize said magnet effectively during discharge of a briny effluent and to cease effective energization during discharge of a fresh water effluent, and means controlled by said magnet to stop the flow of brine to the softener when the magnet becomes effectively energized and to terminate the flushing operation when the magnet loses its effective energization. 100
- 105
47. In a water softener having water supply and brine supply connection and service and drain delivery connections, a normally closed brine valve, valve means normally opening the service connection and closing the drain connection, the 110 said brine valve and valve means being operable to establish a flow of brine through the softener to the drain with the service connection closed, an electromagnet having a circuit controlled by the effluent discharged to the drain to energize 115 said magnet effectively during the discharge of a briny effluent and to cease effective energization during discharge of a fresh water effluent, and means controlled by the magnet to close the brine valve when the magnet becomes energized and 120 to maintain the said valve means in position to keep the drain connection open and the service connection closed until the magnet ceases to be effectively energized and then to restore said 125 valve means to normal position. 130
